UNITED STATES PATENT OFFICE.

PHILIP J. HANDEL, OF MERIDEN, CONNECTICUT.

CASING FOR LIGHT-FIXTURE STEMS.

No. 909,405.

Specification of Letters Patent. Patented Jan. 12, 1909.

Application filed March 9, 1908. Serial No. 419,865.

To all whom it may concern:

Be it known that I, PHILIP J. HANDEL, a citizen of the United States, and a resident of Meriden, in the county of New Haven and State of Connecticut, have invented certain new and useful Improvements in Casings for Light-Fixture Stems, of which the following is a specification.

The object of my invention is to produce a casing for the supporting stems of light fixtures of inexpensive and simple construction and one which can be readily put in place.

Light fixtures adapted for use either with gas or electricity have heretofore usually been supported on a tubular stem which provides a conduit for the gas and also for the electric wires. Fixtures designed solely for the use of electricity are often hung on supports of fanciful design; for instance, in some cases the electric wires are woven in and out of the links of the chain in order to conceal them as much as possible.

The tubular stem is the preferable form of suspension for light fixtures as by its use either gas or electricity, or both, may be utilized and the electric wires are well protected and concealed. The object of my invention is to provide such a tubular stem with a casing which will give the stem a pleasing appearance or a fanciful shape, my casing being so constructed that it can be readily applied to a fixture either after or before it is put up.

In the drawings—Figure 1 is a general view of my invention. Fig. 2 is a detail of one of the links. Fig. 3 is a top view of the same. Fig. 4 is a bottom view of the same. Fig. 5 is a view of a modification. Fig. 6 is a top view of the same. Fig. 7 is a bottom view of the same. Fig. 8 is a perspective view illustrating the parts of the modified device assembled.

My casing is made up of a series of detached sections located end on end, one above another, an aperture extending down through said sections from top to bottom of the series to receive the tubular stem.

In the embodiment of the invention illustrated in the drawings the casing gives the appearance of a chain; each link is made separate from each other link. In the form of

the device illustrated in Figs. 1 to 4, the links *a* are made solid and have hubs *b b'* at top and bottom which are pierced to fit about the tubular stem. On one end of each link there is a projecting lug *c* and at the opposite end a recess *d*. The lug on one link fits into the recess in the other link so as to hold the links in a fixed relation to one another. As shown the lugs and recesses are quartered with respect to one another so that when several links are placed end on end the casing takes the appearance of a chain whose links are arranged at right angles to one another.

As seen in Figs. 5 to 8, each link is made in two separate parts, 1, 2, each part having an inwardly extending bifurcated projection 3, 4, at each end thereof, and pins 5 on one of the projections which take into recesses 6 in the other projection. When these two parts are brought together, as shown in Fig. 8, they have the appearance of a solid link with end hubs pierced to receive the tubular stem. Such a construction as will be readily apparent can be applied to a fixture already in place.

I claim:

1. A casing for the supporting stems of light fixtures comprising a series of detached members arranged one above another and having an aperture extending through said members from top to bottom of said series to receive said stem, each of said members being formed in two parts, and interengaging devices on said parts.

2. A casing for the supporting stems of light fixtures comprising a series of detached members arranged one above another, each of said members being formed in two parts, bifurcated projections from each end of each of said parts forming an aperture extending through said members from top to bottom of said series to receive said stem, said parts being provided with interengaging devices.

3. A casing for the supporting stems of light fixtures comprising a series of detached links arranged one above another and each having a hub at each end for the passage of the stem, one of the hubs of each link being provided with a vertically extending pin and the other of the hubs of each link being pro-

vided with a recess, said pins and recesses constituting interengaging means for the said links.

4. A casing for the supporting stems of light fixtures comprising a series of detached members arranged one above another and each consisting of a pair of vertically extending arms formed integrally at their top and bottom with means to constitute an annular

hub for the passage of the stem, said hubs extending at right angles with respect to the body portion of said arms, and interengaging means between said members on said hubs

PHILIP J. HANDEL.
